UNITED STATES PATENT OFFICE.

DAVID B. KIRSCHNER, OF NEW YORK, N. Y.

RACK FOR GARMENT-POCKETS.

SPECIFICATION forming part of Letters Patent No. 577,483, dated February 23, 1897.

Application filed June 24, 1896. Serial No. 596,681. (No model.)

To all whom it may concern:

Be it known that I, DAVID B. KIRSCHNER, a citizen of Russia, and a resident of New York city, New York, have invented an Improved Rack for Garment-Pockets, of which the following is a specification.

This invention relates to a rack which is secured within the pocket of a garment and is adapted to retain pencils, combs, and similar articles in such a way that they are readily accessible and are not liable to become broken.

In the accompanying drawings, Figure 1 is a side view of a vest provided with my improved rack. Fig. 2 is a section on line 2 2, Fig. 1; Fig. 3, a front view of the rack; Fig. 4, a cross-section on line 4 4, Fig. 3; Fig. 5, a rear view of the rack; and Fig. 6, a longitudinal section on line 6 6, Fig. 5.

My improved rack is composed, essentially, of a textile body, an elastic band or retainer secured to the front thereof, a stiffener secured to the rear thereof, and a series of transverse clips for connecting the parts and dividing the retainer into compartments.

The letter *a* represents the textile body, which is preferably folded upon itself to inclose a layer of haircloth *b*. To the front of the body *a* there is secured, by means of the wire clips *c*, an elastic band or retainer *d*, which forms the rack proper and is by the clips subdivided into a number of compartments that are adapted to receive the pencils, combs, or other articles A. Back of the elastic band *d* there is secured to the body *a* a flat stay or stiffening-rib *e*, which prevents the

band from folding transversely upon itself. This stay is attached to the fabric *a* by means of the clips *c*, the prongs of which are projected through the fabric and are clenched around the stay. Thus the clips serve the purpose of attaching and subdividing the band and also of attaching the stay.

In order to prevent longitudinal displacement of the stay, I secure to the end clips *c'* 45 the hooks *f*, that engage the edges of the stay.

The fabric *a* should be of such a width as to project both above and below the band and stay. Thus flaps are formed that may be stitched to the lining of the garment-pocket *B*. The rack is preferably secured within a vest-pocket at a short distance below the mouth thereof. In this way it may be readily charged with pencils and similar articles, which are thus secured in place in 55 an orderly manner and are prevented from being broken.

What I claim is—

1. A rack for garment-pockets composed of a textile body, a front elastic band, a rear stay, and transverse clips, substantially as specified.

2. A rack for garment-pockets composed of a textile body, a front elastic band, a rear stay, transverse clips, and a pair of hooks 65 that engage the edges of the stay, substantially as specified.

DAVID B. KIRSCHNER.
